UNITED STATES PATENT OFFICE

JABEZ H. PRATT AND FRANKLIN B. HUNT, OF CHICAGO, ILLINOIS, ASSIGNEES, BY
MESNE ASSIGNMENTS, TO THE LIQUID CARBONIC CORPORATION, OF CHICAGO,
ILLINOIS, A CORPORATION OF DELAWARE

COOLER CABINET

Application filed March 6, 1926. Serial No. 92,745.

This invention relates to improvements in cooler cabinets adapted for use in connection with soda fountains and other places where ice cream is sold and the principal purpose 5 of the present invention is to provide an improved construction of the covers and upper parts of the cooler cabinet whereby a cold temperature is more effectively maintained in the upper parts of the containers for the ice 10 cream. The principal object of the invention is to provide an improved cover construction for cooler cabinets. A further object is to provide an improved construction of the upper part of an ice cream receptacle 15 whereby cooler temperatures are maintained surrounding the upper part of the ice cream container. Other objects relate to various features of construction and arrangement which will appear more fully hereinafter.

20 The nature of the invention will be understood from the following specification taken with the accompanying drawings in which one embodiment is illustrated. In the drawings, Fig. 1 shows a top plan view of 25 the improved cooler cabinet; and Fig. 2 shows a longitudinal vertical section taken on the line 2—2 of Fig. 1.

The improved ice cream cabinet may be of any desired extent and embody any desired 30 number of ice cream receptacles, but in the accompanying drawings it has been deemed sufficient to show the improvements in connection with a single ice cream receptacle and its associated cover. The cooler cabinet, des- 35 ignated generally by the numeral 10, has a horizontal top capping 11 formed preferably of metal or the like, having a smooth upper surface, and this capping is provided above the location of the ice cream receptacle with 40 an up-turned flange 11^a surrounding an aperture into which extends an annular ring 12 formed preferably of a relatively hard and strong non-conducting heat insulating material, such as bakelite, which is molded in the 45 desired shape. The body portion 12^a of this insulating ring is tapered downwardly and inwardly and is adapted to fit closely an aperture 13^a which is formed in the top frame 14 formed preferably of wood. The 50 ring 12 is provided at the upper edge of the

body portion 12^a thereof with an outwardly and downwardly turned annular flange 12^b which has its lower edge 12^c resting directly on and in close contact with the upper surface of the top capping 11. It will be apparent that the up-turned flange 11^a of the top capping extends upwardly within the space beneath the down-turned flange 12^b of the insulating ring, thus forming a substantially fluid-tight joint. The annular insulating ring 12 is further provided adjacent the lower part thereof with an annular inwardly directed horizontal shoulder 14 upon which the receptacle cover 15 is adapted to rest, as hereinafter more fully described. 55 The downwardly extending annular part 12^d of the insulating ring which lies below the annular shoulder 14 is under-cut to receive the upper edge of a cylindrical metal plate 16 which is secured to the insulating ring by 60 means of bolts 17. The metallic annular ring 16 which is of the same cross-sectional shape as the annular ring 12 has its lower edge secured by bolts 18 to the jacket or wall 19 which forms the ice cream receptacle proper 65 and which is adapted to receive one or more ice cream containers shown by dotted lines and indicated by the numeral 20. The space around the annular sheet metal ring 16 is 70 filled with cork 21 or other suitable heat insulating material and the space around the metallic shell or wall 19 is occupied by brine or other suitable refrigerating means by which a low temperature is maintained within the ice cream receptacle. In the embodiment 75 illustrated, the shell or wall 19 is offset laterally at one side as shown at 19^a so that the body portion of the receptacle beneath the metallic ring 16 is larger in cross section than the opening closed by the cover 15, thus permitting one ice cream container 20 to be inserted and moved laterally beneath the offset portion 19^a before another container 20 is put in place within the cabinet. With this 80 construction, the brine or other cooling medium in the region surrounding the receptacle 19 serves to maintain a low temperature of the contents of the containers 20 and the 85 upwardly extending metallic ring 16 which has a direct heat conducting connection with 90 95 100

the shell 19 serves to maintain a low temperature in the region adjacent to the upper part of the containers 20 so that when the containers are filled with ice cream, the upper portions of the ice cream are maintained at a lower temperature than has been possible with ice cream cabinets of the form heretofore used, this improvement being due to the presence of the metallic ring 16 of low temperature surrounding the space immediately above the ice cream containers.

The cover 15 comprises two sections 15^a which are connected centrally by hinges 22, the composite cover having a cross-section of oval or other desired shape conforming to the shape of the insulating ring 12 on which it is mounted. Each section 15^a of the cover comprises a body portion 23 formed of a suitable tough and strong heat insulating material, such as bakelite, which is molded into the desired semi-circular or semi-oval shape, having a top wall 23^a, a downwardly directed transverse wall 23^b, at the center of the cover, and a curved wall 23^c which extends downwardly from the outer edge of the top wall 23^a and unites the opposite ends of the transverse wall 23^b. The top wall 23^a is preferably sloped downwardly and outwardly from the transverse wall 23^b to which the hinges 22 are connected, and around the curved outer edge of the top wall 23^a, there is provided an outwardly and downwardly turned flange 23^d which overlaps the top edge of the insulating ring 12 and projects downwardly slightly beneath the top edge of that ring, substantially into the recess 12^e which is formed in the outer face of the down-turned flange 12^b. Centrally located handles 24 are provided on each of the cover sections 15^a, these handles having screw-threaded studs 24^a which engage threaded members 25 embedded in the body portion 23 of the cover. The top walls and downwardly extending walls of each cover section 15^a form a chamber 26 which is filled with cork 27 or other suitable heat insulating material. This heat insulating material is maintained in place by means of removable metal plates 28 having bright lower surfaces, which are secured to the body portions 23 of the cover sections by means of screws 29 threadedly engaging sprocket members 30 which are embedded in the molded material of the body portions 23. The outer edges 28 of the metal plates 28 are directed upwardly and serve to retain in place the rubber sealing and cushioning strips 32 which seat against the lower edges of the walls 23^b and 23^c of the cover sections and which are provided with tubular resilient portions 32^a located adjacent to and outside of the edges of the metal plates 28, as shown in Fig. 2. These rubber sealing rings are adapted to rest on the annular ledge 14 which is formed on the annular ring 12, thereby providing a seal between the cover and

the wall of the receptacle so that air cannot enter from outside the cabinet. The portions 32^a of the sealing rings which are located beneath the transverse walls 23^b of the two cover sections are adapted to contact with each other so that they form a substantially air-tight seal adapted to prevent the transfer of heat downwardly between the two cover sections 15^a. In addition to their function of maintaining the heat insulating material 27 in place within the cover sections, the metallic plates 28 serve also to transfer to the cool side walls of the chamber any heat present in the upper part of the chamber beneath the cover, so that they contribute to the maintenance of a relatively low temperature adjacent the upper parts of the ice cream containers 20.

It will therefore be apparent that the present invention provides improved means for transferring the cold temperature upwardly from the refrigerated wall of the ice cream receptacle to the region surrounding the upper parts of the ice cream containers, and that the improved cover construction serves not only to prevent transfer of heat through the cover and around the edges thereof to the interior of the receptacle, but that it also serves by radiation and reflection to maintain a cold temperature in the upper part of the ice cream containers where the ice cream ordinarily tends to become too soft to be served to the customers. The improved construction and arrangement of the cover in combination with the annular insulating ring 100 and the top capping of the cabinet serve to promote sanitation and cleanliness, in addition to contributing to the attractive appearance of the top part of the ice cream cabinet.

Although one form of the invention has been shown and described by way of illustration, it will be understood that it may be constructed in various other embodiments within the scope of the appended claims.

We claim:

1. A cooler cabinet comprising a flat metallic top capping having an aperture therein, said top capping having a flange directed upwardly around said aperture, and an insulating ring mounted in said aperture and having a flange directed downwardly and outwardly over said flange on said capping.
2. A cooler cabinet comprising a flat metallic top capping having an aperture therein, an insulating ring of molded material mounted in said aperture and having an inwardly directed annular shoulder, and a heat insulating cover mounted on said shoulder.
3. A cooler cabinet comprising a flat metallic top capping having an aperture therein, a heat insulating ring of molded material mounted in said aperture and having an annular flange resting on said top capping, said heat insulating ring having an inwardly

directed annular shoulder, and a cover having an annular resilient member mounted on said annular shoulder.

4. A cooler cabinet comprising a top capping having an opening therein, a cover mounted within said opening and having a top wall and integral lateral walls formed of molded heat insulating material, a metallic wall forming the bottom of said cover and having its edges secured to said insulating lateral walls, and heat insulating material mounted within the walls of said cover, said cover comprising two similar sections connected by hinges having their parts embedded in said molded heat insulating material.

5. A cooler cabinet comprising a metallic top capping having an aperture therein, a ring of molded insulating material engaging said capping and extending downwardly within said opening, and an annular metal receptacle wall connected to the lower part of said insulating ring and extending downwardly therefrom, said metallic capping being spaced from said metal receptacle wall by said molded insulating ring.

6. A cooler cabinet comprising a top capping having an opening therein and a cover mounted within said opening, said cover comprising a top wall and integrally formed annular depending walls formed of molded insulating material, other insulating material mounted within said walls beneath said top wall, and a metallic wall for said cover attached to the lower edge of said annular wall.

7. A cooler cabinet having an opening provided with a cover, said cover comprising two complementary top wall sections formed of molded insulating material and each provided with annular depending walls, hinges having parts embedded in said molded heat insulating material and connecting said cover sections, other heat insulating material mounted within said annular walls of said cover sections, and metallic lower walls detachably secured to said annular walls of said cover sections.

In testimony whereof, we have subscribed
to our names.
